UNITED STATES PATENT OFFICE.

JERMAIN CHANDLER, OF TOLEDO, OHIO.

DISPENSING APPARATUS.

1,420,080.

Specification of Letters Patent. Patented June 20, 1922.

Application filed August 10, 1921. Serial No. 491,265.

To all whom it may concern:

Be it known that I, JERMAIN CHANDLER, a citizen of the United States of America, residing at Toledo, Lucas County, Ohio, have 5 invented new and useful Dispensing Apparatus, of which the following is a specification.

This invention relates to the control of the feeding of strip material.

10 This invention has utility when incorporated in dispensing apparatus for sanitary towels, toilet paper, etc.

Referring to the drawings:

Fig. 1 is a perspective view of an embodiment of the invention for dispensing paper towels from a roll of such stock;

Fig. 2 is an elevation of the charging end of the dispensing apparatus of Fig. 1;

20 Fig. 3 is an elevation of the feed control end of the apparatus;

Fig. 4 is a longitudinal section of the mounting or outer shell of the apparatus, other portions being partially broken away;

25 Fig. 5 is a fragmentary perspective view of the roll release and actuator; and

Fig. 6 is a partial section on the line VI-VI, Fig. 3.

Screws 1, through brackets 2 serve to anchor the outer housing or mounting 3 in 30 position against a support or wall 4. This tubular housing 3 has an open end 5 adjacent which is a hinge 6 for a gate 7 swingable into closed position to be locked by a lock 8. This gate 7 has central bearing 35 opening 9 for trunnion 10. This trunnion 10 thereby mounts one end of roll support 11 as a U-shaped metal strip providing a rectangular core, the trunnion 10 being in the bend of the U-portion thereof. The free 40 ends of the U-support 11 are riveted to a disk 12, having inwardly struck out portions 13 as engaging or anchoring means for embedding into the end of a roll 14 of strip material, as paper towels. Outwardly struck-up fingers 15 from the disk 12 engage flange 16 from tubular bearing 17 concentric with closed end 18 of the housing 3.

Within this outer stationary bearing member 17 is inner bearing member 19 having 50 fixed therewith element 20 anchored to the support 11, 12, and to extensions 21, say by spot welding. These extensions 21, have weakened or resilient portions 22 and then form a pair of opposing U-shaped or channel grips housing a spring 24 normally thrusting these handle or grip portions out-

wardly, to have clutch element portions 25 thereof in engagement with opposing clutch element portions 26 of collar 27 carried by the disk or mounting end 18, and in axial 60 alignment with the bearings 17, 9.

In operation a free end of paper from the roll 14 may protrude through opening 28. In order to obtain a section of such paper, pulling thereon will not unwind it from 65 the roll, but will only draw it up toward the side of the opening 28 to be torn off at such region. To effect paper delivery, the end of the paper from the roll 14 should be lightly pulled through the opening 28, and the handle or grip portions 23 grasped with the other hand and so squeezed as to be flexed upon the weakened or resilient portions 22 that toothed or clutch elements 25 are withdrawn from the clutch elements 26, and as 70 so withdrawn, the handle 23 is then rotated to turn the roll support 11 and with it the roll 14 so that the paper may be withdrawn from the mounting 3 through the opening 28 of the desired length.

80 It is contemplated the clutch release by the grip shall be awkward and fatiguing for continued operation, to the end that the paper may not be misused, but only taken in such small portions as actually needed, 85 thereby conserving the supply. The open end of the housing permits a convenient charging of a supply renewing roll upon the support 11, as a supply is exhausted therefrom. Furthermore this open end 5 90 permits observation of the roll and working of a free end of the paper down toward the opening 28 in the event there may be a break in the continuity of the strip on the roll.

95 What is claimed and it is desired to secure by Letters Patent is:

1. A support for a roll of strip material, said support being provided with roll engaging means, a mounting for the support in which the support is rotatable, a handle 100 for operating the support, and a clutch releasable by shifting a handle and normally holding the roll and support against rotation as to the mounting.

105 2. In the carrying of a roll of strip material, a support for the roll provided with roll engaging means, and a mounting for the support in which mounting the support is rotatable embodying a clutch, said support being provided with an actuating handle, there being engaging means between the clutch and handle normally precluding op-

- eration of the support as to the mounting, said handle including means shiftable as to the clutch for freeing the support for rotation from the handle.
5. 3. A carrier for a roll of strip material embodying a roll support provided with roll engaging means, and a support mounting in which the support is rotatable, said support being provided with a handle including means shiftable as to the mounting.
10. 4. A strip material roll carrier embodying a roll support provided with roll anchoring means, and a support mounting in which the support is rotatable, said support being provided with a yieldable grip handle as a clutch element and said mount-

ing being provided with a coacting clutch element, whereby to operate the support the handle must be shifted into clutch releasing position.

5. A strip material roll carrier embodying a roll support provided with roll anchoring means, and a support mounting in which the support is rotatable, said support being provided with a pair of opposing grip portions and a spring thrusting the grip portions apart, and said mounting being provided with a clutch element against which said gripping portions are thrust by the spring into roll holding position.

In witness whereof I affix my signature.
JERMAIN CHANDLER.

Certificate of Correction.

It is hereby certified that in Letters Patent No. 1,420,080, granted June 20, 1922, upon the application of Jermain Chandler, of Toledo, Ohio, for an improvement in "Dispensing Apparatus," an error appears in the printed specification requiring correction as follows: Page 2, line 8, claim 3, after the word "rotatable" and before the comma insert the words *embodying a clutch*; and that the said Letters Patent should be read with this correction therein that the same may conform to the record of the case in the Patent Office.

Signed and sealed this 11th day of July, A. D., 1922.

[SEAL.]

KARL FENNING,

Acting Commissioner of Patents.
